Mark C. Lissner,
ATTORNEY

UNITED STATES PATENT OFFICE

FREDERICK WOODRUFF, OF EAST ORANGE, NEW JERSEY

HOLDING DEVICE

Application filed October 10, 1929. Serial No. 398,590.

This invention relates to devices adapted to prevent towels and similar articles from slipping from towel racks.

The usual towel racks employed in bath room and similar places are made of glass, or highly polished metal, and unless the towel is properly balanced thereon, the smooth surface of the rack offers insufficient resistance to prevent the towel from slipping therefrom. The constant slipping of towels from racks is a source of annoyance and renders it inconvenient for a housekeeper to maintain a neat appearance in a bath room.

It is an object of this invention to provide a simple device which may be readily and conveniently placed over a towel to prevent it from slipping from a towel rack.

This and other advantageous objects are accomplished by the novel construction hereinafter described and illustrated in the accompanying drawings, constituting a material part of this disclosure and in which:

Figure 1 represents a perspective view showing an application of the invention.

Figure 2 represents a perspective view of a modified form of the invention.

Figure 3 represents a side elevational view of my device suspended from a horizontal bar or towel rack showing the manner in which the lower leg portion of the device, owing to the overbalanced structure employed, swings inward and engages with the side of the towel adjacent thereto.

Referring to the drawings the device is shown to comprise a polished rod bent to form a U having straight vertical legs 3 and 4 with a horizontal connecting portion 5, the upper ends of the legs 3 and 4 being curved and bent slightly downward to provide the arcuate portions 6 and 7, the extremities of which are connected by the horizontal rod 8. The legs 3 and 4 are of such length and weight as to bring the center of gravity of the device, when in use, below the axis of the rack 10, as clearly shown in Figure 3.

In operation the device is positioned on a towel or the like 9 supported on a rack 10. The arcuate portions 6 and 7 of the device, which are of greater diameter than the rack 10 and article suspended thereon, encircle the

portion of the towel which embraces the rack and the vertical legs 3 and 4 owing to the overbalanced structure of the device swing inwardly and bear against the side of the towel as clearly indicated in Fig. 3.

In Fig. 2 of the drawing I have shown a modified form of the device wherein the lower extremities of the legs 3' and 4' are not connected by a horizontal portion but are provided with spherical caps 10' and 11 adapted to engage the side of the towel and to prevent the free ends of the legs from tearing or fraying towels or other articles which may be on the rack.

The length of the legs 3 and 4 and the weight of the horizontal portion 5 and of the caps 10' and 11 may be varied to meet requirements of various articles supported on the rack.

From the above description, it will be seen that I have provided a simple device which may be readily and conveniently applied for preventing slipping of articles supported on the horizontal bar.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention what I claim as new and desire to secure by Letters Patent, is:

1. A device for preventing an article overhanging a horizontal rack from slipping therefrom, comprising arced members having a greater diameter than the diameter of the rack and article thereon, and elongated members depending from one end of the arced members, said elongated members being of such length and weight as to bring the center of gravity of the device below the axis of the rack when in use, the distance between the lower ends of the depending members being greater than the diameter of the rack and article thereon.

2. A device for preventing an article overhanging a horizontal rack from slipping

therefrom, comprising arced members having a greater diameter than the diameter of the rack and article thereon, elongated members depending from one end of the arced members, and spherical caps at the ends of said elongated members, the elongated members being of such length and weight as to bring the center of gravity of the device below the axis of the rack, when in use, the distance between the lower ends of the depending members being greater than the diameter of the rack and article thereon.

10 This specification signed this 9th day of October, 1929.
